UNITED STATES PATENT OFFICE.

CARL J. SUNDELL, OF CHICAGO, ILLINOIS.

CONVERTIBLE HIGH CHAIR.

1,334,058.

Specification of Letters Patent. Patented Mar. 16, 1920.

Application filed October 20, 1919. Serial No. 332,111.

To all whom it may concern:

Be it known that I, CARL J. SUNDELL, a citizen of the United States, and a resident of Chicago, in the county of Cook and State 5 of Illinois, have invented certain new and useful Improvements in Convertible High Chairs, of which the following is a specification.

This invention relates to improvements in 10 a convertible article which may be used practically for the service of children, or if desired, so that it can be employed by them as a toy, or in play, and it consists in certain peculiarities of the construction, novel 15 arrangement and operation of the various parts thereof, as will be hereinafter more fully set forth and specifically claimed.

The principal object of the invention is 20 to provide a highly useful article, which shall be simple and inexpensive in construction, strong, durable, and efficient in operation, which can be used practically as a high chair or a baby carriage, from one form 25 to another of which devices it can be readily and quickly converted; or if desired, it can be constructed, of proper size and material, and be used by children as a toy for dolls, in which event, the same construction and convertibility will be maintained.

30 Other objects and advantages of the invention will be disclosed in the subjoined description and explanation.

In the accompanying drawings, which 35 serve to illustrate an embodiment of the invention,

Figure 1 is a view in side elevation of the device with its parts arranged in the form of a high chair for babies having a table or platform mounted on the arm rests of said 40 chair.

Fig. 2 is a front face view thereof.

Fig. 3 is a view in side elevation illustrating by continuous lines the position the parts will occupy when converted into a 45 baby carriage, and by dotted lines, the position thereof in the form of a high chair. Said view also showing by dotted lines a canopy supported on and over the carriage.

Fig. 4 is a sectional view taken on line 50 4-4 of Fig. 3 looking in the direction indicated by the arrows.

Fig. 5 is a side view of the upper portion of the device when formed into a baby carriage illustrating the canopy mounted 55 thereon, but showing portions of one side of

the canopy broken away to exhibit parts of the support thereof.

Fig. 6 is a vertical sectional view taken on line 6-6 of Fig. 3 looking in the direction indicated by the arrows. 60

Fig. 7 is a detached front view of the canopy supporting yoke and its roller or bar, and

Fig. 8 is a side view of a portion of one of the supporting arms for the canopy. 65

Like numerals of reference refer to corresponding parts throughout the different views of the drawings.

Referring now more particularly to Figs. 1 to 4 inclusive of the drawings, it will be 70 seen and understood that the supporting frame of the device includes two pairs of spaced apart supporting members, each pair consisting of two bars 10 and 11 crossed a little below their longitudinal middles and 75 pivotally connected together by means of a rod 12 which extends from one of the supporting members to the other. That portion of the bars 10 below their pivots 12 constitutes the front legs of the chair, and that 80 portion of said bars above their pivots 12 constitutes a portion of the back of the device. That portion of the bars 11 located below their pivots 12 constitutes the rear legs 85 of the device, while the upper portions of said bars constitute the upper front part of the supporting frame.

The parallel bars 10 are braced near their lower ends by means of a transverse rod or bar 13 and the bars 11 are similarly braced 90 near their lower ends by means of a like connection 14. As shown in Figs. 1, 3 and 4 of the drawings, each of the legs or bars 10 and 11 is provided in its lower end with an upwardly extended slot 15 which are for the 95 reception of axles 16, each of which consists of a flat body portion to fit in said slots, and is provided at each of its ends with a cylindrical portion 17 on which the hubs of the wheels 18 are mounted for rotation and are 100 held in place by means of cotter-pins 19 extended through suitable transverse openings in the portions 17 of the axles.

Longitudinally mounted on the outer surface of each of the bars 10 and 11 is a 105 strengthening plate 20, each of which has in its lower end a slot 21 to receive the axles 16 when it is desired to convert the device into a carriage. Each of the plates 20 is detachably secured to its supporting bar by means 110

of a screw 22 and thumb nut 23 engaging the same, said screws being located in the upper ends of said plates. The lower end of each of the plates 20 is held in place by 5 means of an angular shaped collar 24 secured to each of the bars 10 and 11 near their lower ends, each of said collars being provided in its lower end with a slot to register with the slots 15 and 21 in the bars 10 and 11 and 10 plates 20 respectively.

Pivotedly mounted on a rod 25 journaled in and connecting the upper portions of the bars 10 at a suitable distance from their upper ends is the back of the chair or device, which consists of a pair of parallel side members 26 connected at their upper and lower ends by cross-pieces 27 and provided with a middle portion or panel 28^a against which the back of the child may rest. Extended outwardly from each of the side members 26 is a handle 28, by means of which the device can be propelled when it is used as a carriage. The side members 26 are transversely united just below the lower cross-piece 27 by means of a rod 29 on which are loosely mounted at their upper ends a pair of bars 30 which are similarly mounted at their lower ends on a cross-rod 31 which is mounted at each of its ends in a bar 32 pivotally mounted on the lower portion of each of the supporting bars 11. Pivotedly connected to each of the bars 32 at the inner end thereof is a link 34 which extends upwardly and is pivotally secured at its upper end to the 35 inner surface of the supporting bar 10 adjacent thereto at a point near the lower end of the back of the device.

Pivotedly secured at one of its ends to the upper portion of each of the supporting members 10 and extended horizontally and forwardly therefrom is an arm rest rail 36 each of which is in telescopic engagement with another arm rest rail 37 each of which is pivotally mounted at its front end on the 45 upper portion of one of the supporting members 11 and is provided with a longitudinally extended slot 38 to receive a screw 39 seated in the member 36 and having on its outer portion a thumb or set nut 40 to be used for fixing the telescopic members or rails 36 and 50 37 together in the desired position.

Located between the upper portion of the supporting members 11 at a suitable distance below the rails 37 thereon is the front portion of a platform 41 which is pivotally connected to the members 11 at its side edges and has at the rear portion of each of its side edges a lateral projection 42 to engage a slotted link 43 one end of which is pivotally connected to the upper portion of each of the supporting members 10 and by preference by means of the pivot rod 25 which supports the back rest of the chair or device. The opposite end of each of the links 43 is 60 65 pivotally connected to one end of a link 44

the other end of each of which is pivotally connected to the supporting members 11 above their pivots 12 and by preference on the brace or tie-rod 45 which unites said supporting members.

Extended forwardly from each of the members 11 at points just below the pivot of the platform 41 is a bracket 46 to each of which is pivotally secured one end of a link 47 the other end of each of which is 70 connected to one end of another link 48 each of which latter named links is pivotally connected at its other or upper end to the side edges of the rear portion of a table or tray 49 which extends across the front portion of 75 the upper part of the supporting frame and overlies and rests on the rails 37 when the device is used as a high chair. The table or tray 49 is provided on its lower surface near each of its ends with a cleat 50 which extend 80 transversely with respect to the table and serve to strengthen the same as well as to act as guides against the inner surfaces of the rails 37 as well as against the inner surfaces of the upper portions of the members 11 of 85 the supporting frame. Each of the supporting members 11 has longitudinally mounted on its outer surface near its upper end a guide rod 51 each of which is formed at its upper end with a rearwardly and 90 downwardly inclined loop 52. These rods engage screw-eyes 53 one of which is located on the front portion of the table or tray 49 near its side edges, as is clearly shown in Fig. 2 of the drawings.

It will be understood that each of the guide-rods 51 is slightly spaced from the members 11 but is secured at each of its ends thereto. A spring 54 is secured at one of its ends to each of the members 11 at points 105 above the lower pivoted ends of the links 44 and is then passed around each of the links 47 and secured at its other end to the pivot which unites the links 47 and 48 on each side of the device.

By this arrangement it is evident that the table or tray 49 when in its position shown in Fig. 1 of the drawings will be held securely in place on the arm rest rails 37 and upper ends of the member 11 by reason of the tension of the springs 54 and by reason of the engagement of the screw-eyes 53 with the loops of the guide-rods 51, yet in such a way that the table may be moved from the position indicated by continuous lines in Fig. 1 of the drawings and by dotted lines in Fig. 3 of the drawings to the position indicated by continuous lines in Fig. 3 where it will form a closure or foot rest for the front end of the frame of the device consisting of the upper portion of the supporting members 10 and 11, the seat or platform 41 and the arm rest rails 36 and 37 at each side of the device, which is desirable when the device is converted into a baby carriage as 110 115 120 125 130

shown by continuous lines in Fig. 3 of the drawings.

As it will be necessary to provide the device with a cover or canopy when the same is used as a baby carriage for out-of-door use, I provide each of the side rails 26 of the adjustable back rest or support at their upper ends and on their rear surfaces with a rearwardly extended plate 55, each of which is provided with a longitudinal slot 56 having a communicating opening 57 at about its middle for the reception of headed projections 58 on each end of a roller 59 which is located transversely on the rear upper portion of the back rest between the plates 55 and has secured thereto one end of the top 60 of a canopy, which top is provided at each of its sides with downwardly hanging portions 61 as is clearly shown in Figs. 5 20 and 6 of the drawings for closing the sides of the body of the carriage.

Pivoted at its ends on the projections 58 of the roller or bar 59 is a yoke 62, the upper portion 63 of which is adapted to extend 25 transversely with respect to the upper portion of the back rest and to be supported in an upright position so as to hold the top 60 of the canopy at a suitable distance from said back rest. The side members of the 30 yoke are provided with offset portions 64 to rest on the inner portions of the handles 28 as is clearly shown in Figs. 3, 5 and 7 of the drawings. At a suitable distance from the front end of the top 60 of the canopy the 35 same has secured to its lower surface a transverse bar 65 to each end of which is secured on its front and rear surfaces a plate 66, each of which is provided with an upright extension 67, thus forming a pair of parallel 40 spaced apart extensions at each of the ends of the bar 65 which extend upwardly and outwardly therefrom, as is clearly shown in Fig. 6 of the drawing.

Pivotaly mounted at one of its ends between the extensions 67 of each of the plates 66 is a supporting arm 68, the lower portion of each of which is provided on its outer surface with a depending plate 69, each of which has an open ended slot 70 50 to engage the screws 39 carried by the arm rest rails 36 on which screws they may be securely fastened by turning the thumb nuts 40 in the proper direction.

When the canopy is in its operative position, it will be understood that the top 60 thereof will rest on the upper ends of the extensions 67 while the sides 61 of the canopy will hang down outwardly of the supporting arms 68 and that the front portion of the top of the canopy as well as the front edges of the sides 61 thereof will extend a slight distance over the upper edge of the table or tray 49 which forms a foot rest or closure for the front end of the 65 carriage body. At its front end the top 60

of the canopy is provided with a number of spaced apart straps 71 which may be secured at their lower ends to buttons 72 on the lower surface of the front part of the seat 41 the front end of which meets 70 the lower end or edge of the table or tray 49 when the same is adjusted to the position shown in Fig. 5 of the drawings.

From the foregoing and by reference to the drawings, it will be readily understood 75 and clearly seen that when the parts are positioned as shown in Figs. 1 and 2 a high chair will be provided, and that the table or tray 49 thereof will serve to hold the child in place on the seat of the chair, as 80 well as afford a support or tray for its toys, play things, and the like. In order to convert the high chair into a carriage, it is only necessary to loosen the thumb nuts 40 on the screws 39, when it is obvious 85 that the supporting members 10 and 11 may be separated at their upper portions by pressing said portions from each other in which operation said parts will assume approximately the positions shown by continuous lines in Fig. 3 of the drawings. The back rest comprising the side rails 26 and interposed panel 28 may then be inclined downwardly from the position shown by dotted lines in Fig. 3 to that indicated 90 by continuous lines in said figure, in which position it will be securely held by means of the links 30 and 34 and the rocking bars 32.

The table or tray 49 can now be changed 100 from the position shown in Fig. 1 to that illustrated by continuous lines in Figs. 3 and 5 of the drawings, where it will be held by reason of the tension of the springs 54 acting on the links 47 and 48 which 105 unite the table or tray 49 to the brackets 46 of the supporting frame. To prevent the possibility of the supporting members 10 and 11 being accidentally moved toward each other at their upper portions, it is obvious 110 that the thumb nuts 40 can be tightened on the screws 39 so as to hold the arm rest rails 36 and 37 in their extended positions as shown by continuous lines in Fig. 3 of the drawings. It is manifest that should 115 the child fall asleep when the device is used as a high chair, said device can be converted from the high chair form to the reclining or baby carriage form without disturbing or awaking the child.

If desired, the canopy can be mounted on the supporting frame by placing the projections 58 on the roller or bar 59 in the slots 56 of the plates 55 as shown in Fig. 3 when it is evident that the yoke 62 can be 125 placed in an upright position as shown in said figure when the top of the canopy can be extended over said yoke. The supporting arms 68 can then be placed in the positions shown in Fig. 6 when it is evident 130

that the plates 69 on the lower ends of said arms can be placed in engagement with the screws 39 of the arm rest rails 37 and held in an upright position thereon by 5 tightening the thumb nuts 40 on said screws.

The front portion of the top 60 of the canopy can then be placed over the upper end of the member 49 and secured in such 10 position by fastening the straps 71 at their lower ends to the buttons 72 on the seat 41 or floor of the carriage body. The sides 61 of the canopy can then be extended on each side of the carriage body as is evident.

15 The wheeled axles 16 can then be placed in the slots 15 and 21 in the lower ends of the supporting members 10 and 11 and the strengthening plates 20 thereon respectively when it is obvious that the structure 20 of the carriage will be completed.

25 As the canopy is detachably secured to the back rest of the device and also detachably supported on the carriage body by means of the supporting arms 68 and is detachably connected to the platform, it is manifest that it can be easily removed, when the cloth of the canopy can be wound up on the roller or bar 59 into a compact form.

30 Having thus fully described my invention, what I claim as new and desire to secure by Letters Patent is—

35 1. In a device of the class described, the combination with a main frame including a pair of spaced apart side members pivotally and transversely connected together between their ends, each of said members consisting of two bars crossed at their pivots, of a platform horizontally and pivotally mounted on and between the front upper portion 40 of one pair of said bars and extended toward the rear upper parts of the other bars, a lateral projection on the rear part of each side of the platform, a jointed and slotted connection engaging each of said 45 projections and pivotally connected at their ends to the bars of each of the side members, a back rest pivotally mounted between the rearwardly and upwardly extended portion of a pair of said bars, and connections 50 loosely uniting the lower portion of the back rest to the lower rear portion of a pair of said bars.

55 2. In a device of the character described, the combination with a main frame including a pair of spaced apart side members pivotally and transversely connected together between their ends, each of said side members consisting of two bars crossed at 60 their pivots, of a platform horizontally and pivotally mounted near its front end on and between the front upper portion of one pair of said bars, a back rest pivotally mounted

on and between the rear upper portion of the other pair of said bars, connections loosely 65 uniting the lower portion of the back rest to the rear lower portion of the first named bars, a lateral projection on the rear part of each side of said platform, a jointed and slotted connection engaging each of said 70 projections and pivotally connected at their ends to the upper portion of the bars of each of the side members, telescoping arm rest rails uniting the upper portions of the bars of each side member, a table mounted transversely 75 on the front portion of said arm rest rails, and spring actuated jointed connections uniting the ends of the table to the forwardly extended portions of said side members.

80 3. In a device of the character described, the combination with a main frame including a pair of spaced apart side members pivotally and transversely connected together between their ends, each of said side members consisting of two bars crossed at their pivots, of a platform horizontally and pivotally mounted near its front end on and between the front upper portion of one pair 85 of said bars, a back rest pivotally mounted on and between the rear upper portion of the other pair of said bars, a rocking bar mounted on the inner surface of the lower portion of the rearwardly extended bars of the side members, a link pivotally connected 90 at one of its ends to the lower portion of the back rest and near its other end to the outer ends of the rocking bars, a link pivotally connected at one of its ends to the inner end of each of the rocking bars and 95 similarly connected at their upper ends to the bars on which the back rest is mounted, a lateral projection on the rear part of each side of said platform, a jointed and slotted connection engaging each of said 100 projections and pivotally connected at their ends to the upper portion of the bars of each of the side members, telescoping arm rest rails uniting the upper portions of the bars of each side member, an upwardly disposed guide-rod 105 mounted on the upper portion of each of the forwardly extended bars and each having a loop in its upper portion, a bracket extended forwardly from each of the forwardly extended bars, a table mounted transversely 110 on the upper portion of the arm rest rails and having near each of its ends means engaging said guide-rods, spring actuated jointed connections uniting the ends of the table to said brackets, and wheeled axles 115 transversely mounted on the lower portion of the bars of the side supporting members.

120 In testimony whereof I have hereunto set my hand, on this, the 14th day of October, 1919.

CARL J. SUNDELL,
